UNITED STATES PATENT OFFICE.

CLAUDE C. HYDE, OF OTISVILLE, NEW YORK.

DESIGN FOR KNITTED FABRIC.

Application filed May 12, 1922. Serial No. 2,204. Term of patent 3½ years.

To all whom it may concern:

Be it known that I, CLAUDE C. HYDE, a citizen of the United States, residing at Otisville, in the county of Orange and State of New York, have invented a new, original, and ornamental Design for Knitted Fabric, of which the following is a specification, reference being had to the accompanying drawing, forming part thereof.

The figure is an enlarged plan view of the knitted fabric showing my new design.

I claim:

The ornamental design for knitted fabric,

CLAUDE C. HYDE.
